(57) CLAIM

The ornamental design for a combination container, grinder, and ashtray as shown and described.

DESCRIPTION

FIG. 1 is a front perspective view of the combination container, grinder, and ashtray showing the new design; FIG. 2 is another front perspective view thereof; FIG. 3 is a top perspective view thereof; FIG. 4 is a bottom perspective view thereof; FIG. 5 is a top perspective view thereof, shown in an opened configuration of use; FIG. 6 is a top perspective view thereof, shown in an opened configuration of use with ashtray removed; FIG. 7 is a top perspective view thereof, showing a top portion removed; FIG. 8 is a top perspective view thereof, showing a top portion and grinder removed; FIG. 9 is a front perspective exploded view thereof; FIG. 10 is a rear perspective exploded view thereof; and, FIG. 11 is a bottom perspective exploded view thereof. The broken lines immediately adjacent the shaded surfaces depict the bounds of the claimed design whereas all remaining broken lines depict portions of the combination container, grinder, and ashtray, all of which form no part of the claimed design.
